UNITED STATES PATENT OFFICE

2,401,597

PIN-TYPE FEEDING DEVICE

Charles L. Winter, Chicago, Ill., assignor to United
Autographic Register Co., a corporation of Illinois

Application January 1, 1944, Serial No. 516,634

2 Claims. (Cl. 271—2.3)

1

This invention relates to pin wheel feeding devices for use in feeding stationery provided with regularly spaced feeding holes, and more particularly to an improved structure for carrying and controlling oscillatable pins on a feed wheel.

The primary object of the invention is to provide an improved feed wheel of simple construction wherein each feed pin is mounted for oscillation in the direction of feed and cam means is provided to control the angular position of the pin while it is in feeding engagement with the paper and then release the pin so that it may withdraw from the feed hole in the stationery without difficulty. Feed wheels of this type may be provided on an attachment for a typewriting machine or tabulating machine and be driven from the platen roll of a machine in the manner shown in my application Serial No. 513,879, filed December 11, 1943.

The invention is illustrated in a preferred embodiment in the accompanying drawing, in which—

Figure 1 is a fragmentary sectional view of a pin wheel embodying the invention; Figure 2, a sectional view, taken as indicated at line 2—2 of Figure 1; Figure 3, an end elevational view of the feed wheel, taken in the opposite direction from Figure 1; Figure 4, a vertical sectional view, taken as indicated at line 4—4 of Figure 2; and Figure 5, a perspective view of one of the pin units.

In the embodiment illustrated, a feed wheel 6 is journaled on a driven shaft 7 and makes a driving connection therewith by means of machine screws 8 which impale arcuate slots 9 in a hub member 10 which is splined to the shaft 7, as indicated at 11. This pin-and-slot connection permits the wheel to be adjusted rotationally with respect to the shaft 7.

The wheel 6 is provided near its periphery with a concentric series of spaced sockets 12 which provide bearings for oscillatable feed units 13. Each of the feed units has a cylindrical base to fit into the socket 12 and has an outwardly extending pointed feed pin 14 to engage perforations 15 in superposed strips of stationery 16, as shown in Figure 4. Each of the feed units is cut away at one end to provide a curved cam face 17 which intersects the axis of oscillation of the feed unit. A cam member 18 is secured to a fixed bracket 19 by means of screws 20 which impale slots 21 in the bracket. The cam member 18 is undercut to provide an inwardly presented cam

2

ring 22 to engage the convex cam faces 17 of the feed units. In the embodiment illustrated the cam member 18 and feed wheel 6 are held together by having the hub 23 of the feed wheel extend through the cam member 18 and a spring ring 24 is snapped into a groove provided on the hub.

As best shown in Figure 4, when the feed wheel is rotated clockwise, the feed pins are rocked into a forwardly inclined angular position on the wheel by the cam 18 acting on the cam faces 17 of the units. The advancing pins then become fully engaged with the paper and draw it along for a portion of the cycle of the wheel and then 15 the pins are released from the cam and are free to rock limply so that they will drop out of the holes 15 in the stationery without difficulty. The pins are thus left free until they again approach the position to be reengaged by the cam 18 and 20 grip the next set of feed holes.

The foregoing detailed description has been given for clearness of understanding only, and no unnecessary limitations should be understood therefrom for some modifications will be obvious to those skilled in the art.

I claim:

1. A pin-type feeding device for perforated strips comprising: a driven wheel, a plurality of spaced feed units journaled concentrically for free oscillation in said wheel, each of said units having an outwardly extending pointed feed pin and an outwardly presented convex cam face which intersects the axis of oscillation of said unit, and a fixed cam member having an inwardly presented cam surface to engage the cam faces of the units only during the feeding portion of their cycle to hold them in proper angular feeding position.

2. A pin-type feeding device for perforated strips comprising: a driven wheel, a plurality of spaced feed units having cylindrical bases journaled in said wheel concentrically for free oscillation forwardly and rearwardly in the direction of rotation, each of said units having an outwardly extending pointed feed pin and a convex cam face by which the outward inclination of the pin can be controlled, and a fixed concave shaped cam to engage the cam faces of some of the feed units during a portion of their cycle to control their inclination and leave the other units free to oscillate loosely on the wheel.

CHARLES L. WINTER.
